UNITED STATES PATENT OFFICE.

MOSES K. BLACKBURN, OF FREDERICKTOWN, OHIO.

FENCE-POST.

No. 798,946.

Specification of Letters Patent.

Patented Sept. 5, 1905.

Application filed January 7, 1905. Serial No. 240,070.

To all whom it may concern:

Be it known that I, MOSES K. BLACKBURN, a citizen of the United States, residing at Fredericktown, in the county of Knox and State of Ohio, have invented new and useful Improvements in Fence-Posts, of which the following is a specification.

My invention relates to improvements in fence-posts.

It has for its object to provide a readily and cheaply constructed fence-post, to securely anchor or brace the fence-posts, and to provide for meeting contingencies, as in building or erecting the fence where the ground or surface is hilly.

Said invention consists of the combination and arrangement of parts, substantially as hereinafter fully disclosed, and particularly pointed out by the claim.

In the accompanying drawings, illustrating the preferred embodiment of my invention, Figure 1 is a side elevation of the latter. Fig. 2 is a detached perspective view of a post. Fig. 3 is a cross-section thereof.

In the practicing of my invention I suitably erect or plant the posts 1 in the ground and pass wire 2, forming each panel, back and forth through openings or holes 3 in said posts, suitably securing said wire at its ends to said posts. Said posts may have strung therebetween from their upper ends a top barb-equipped wire 4 for obvious purposes and are guyed or braced in position by suitably wiring the same, as at 5, to anchors or boulders, one or more, buried in the surface or ground after securing the wires or cables to said boulder or boulders by passing and twisting the lower portion about the boulder and twisting the lower end into a substantial

knot about the body of the wire just above the anchoring-boulder, said wires or cables being passed at their upper portions through the desired holes 6 in said posts, according to the points it may be most effective for that purpose. By suitably distributing the wire-receiving holes or openings 3 throughout the length of the posts the wire for each panel may be passed or roved back and forth there-through, with the strands or stringers thus

formed removed a greater or less distance apart, as may be desired. Each post is preferably produced of a metal plate right-angled in cross-section set in a concrete base or anchor 1^a, either formed by making a suitable excavation for the lower end of said post and filling in

around the latter with the concrete or by molding around said post to form said base above ground and when hardened sinking the whole into the excavation, thus providing for protecting the post at that point as against premature impairment or destruction, as would otherwise be the case. Said posts have their wire or stringer receiving openings 3 slotted, the lower half of the series of each post having upward-inclined entrance-slits 3^a and the upper half 65 of said series having downward-inclined entrance-slits, as at 3^b, with, say, the upper walls or edge portions 3^c of the lower slits initially deflected in one direction, while the lower walls or edge portions 3^d of the upper slits are oppositely deflected. Said arrangement of the wire-receiving openings or holes with their oppositely-inclined entrance-slits provide—70 as, for instance, where the posts are planted on a hillside or at the foot thereof—more readily than would otherwise permit for directing the wire into said openings and aiding the more effective holding thereof until the closing of said openings and even after such closing, as in passing the wire upward 75 through said openings and then in passing the said wire downward along the declivity, as in stringing it between and upon said posts. After thus stringing or passing the wire the deflected edge portions or walls 3^c 3^d are returned to their former position or in alignment with the surface of the post, which may be readily effected by improvising of a suitable piece of metal or iron an anvil and holding it against or upon one side of the post and then 80 hammering the deflected portions of the entrance-slits of said openings into alignment edgewise with said post.

It will be noted that the use of staples and the like employed in the erecting of many 95 kinds of fences is herein dispensed with, while the invention is characterized for great simplicity and cheapness and is readily applied.

Latitude is allowed as to details herein, as they may be changed as circumstances suggest without departing from the spirit of my invention and the latter still be protected.

I claim—

A fence-post of the character described, composed of metal of right-angled cross-section, secured at its lower end in a molded concrete base anchored below the surface, one flange or arm of said post being provided with two sets of slotted openings, having laterally-deflected closing-flanges, and the other flange 105 110

or arm of the post being provided with a plurality of guy or brace wire receiving openings, in combination with molded concrete anchors or boulders buried in the ground, and
5 guy-wires secured to said anchors or boulders by passing and twisting the lower portion of each about the boulder and twisting the lower end into a substantial knot about the body of the wire just above the anchoring - boulder,
10 said wires or cables being passed at their up-

per portions through the said brace-wire-receiving openings and fastened therein.

In testimony whereof I have signed my name to this specification in the presence of two witnesses.

MOSES K. BLACKBURN.
